GUN SIGHT

Maynard P. Buehler, Oakland, Calif.

Application August 5, 1949, Serial No. 108,764

2 Claims. (Cl. 33—50)

1

This invention relates to gun sights, and more particularly to a detachable or auxiliary sight to be substituted for a telescopic sight should the latter become damaged or be removed for other reasons.

It is among the objects of the invention to provide a detachable or auxiliary gun sight of small size and light weight which can be quickly and easily mounted on a telescopic sight mount when the telescopic sight is removed, which auxiliary sight is fully adjustable for elevation and windage, comprises a minimum number of simple parts, and is easily manufactured to fit different types of telescopic sight mounts.

Other objects and advantages will become apparent from a consideration of the following description and the appended claims in conjunction with the accompanying drawing, wherein:

Figure 1 is a side elevation of a fragmentary portion of a gun showing a telescopic sight mount thereon and an auxiliary gun sight illustrative of the invention operatively mounted on the telescopic sight mount;

Figure 2 is a top plan view of the telescopic sight mount and the auxiliary gun sight illustrated in Figure 1;

Figure 3 is a side elevation of the rear portion of the telescopic sight mount and of the auxiliary sight with a portion of the auxiliary sight broken sight mount and the auxiliary gun sight illustrate the construction thereof;

Figure 4 is a rear elevation of the telescopic sight mount and the auxiliary gun sight;

Figure 5 is a transverse cross-section on an enlarged scale on the line 5—5 of Figure 2;

Figure 6 is a top plan view on an enlarged scale of the rear end portion of the telescopic sight mount;

Figure 7 is a face elevation of a sight plate constituting an operative component of the auxiliary sight mount;

Figure 8 is a side elevation of a button used in connecting the sight plate illustrated in Figure 7 to the support or base plate illustrated in Figure 9; and

Figure 9 is a perspective view of a supporting or base plate constituting an operative component of the auxiliary gun sight.

With continued reference to the drawing, the telescopic sight mount is generally indicated at 10 and comprises a rigid, metallic body of elongated, rectangular, cross-sectional shape having an elongated, rectangular cross-section. Intermediate its length this body is provided with an elongated notch 11 extending inwardly from one

2

side of the body so that the body has a rectangular front-end portion 12, a rectangular rear-end portion 13, and an intermediate portion 14 interconnecting the front and rear end portions. The front-end portion 12 is cylindrically recessed on its under side to receive the upper portion of a rifle barrel and is provided with two spaced-apart screw holes 15 which receive screws for attaching the mount to the rifle barrel. Near its front end 10 the portion 12 is provided with an opening 16 to receive the post of a telescopic sight and between this opening 16 and its front end the portion 12 is centrally split, as indicated at 17, and a clamp screw 18 extends transversely through the split portion to clamp the telescopic sight post in the opening 16.

The rear portion 13 is also recessed to receive the upper part of the rifle barrel and is provided with an opening for a screw 19 which attaches 20 the rear part of the mount to the rifle barrel.

The notch 11 provides clearance for the cartridge ejector mechanism of the rifle. Near its rear end the mount 10 is provided with a transverse aperture 20 and this aperture is provided in 25 its respectively opposite ends with oppositely-directed screw threads. Two windage screws 21 and 22 are threaded into the respectively-opposite ends of the transverse aperture 20 and each of these screws has an enlarged, cylindrical head 23 30 provided in its outer surface with a screw driver slot 24 and having its inner surface circularly concave, as indicated at 25. Counterbores are provided in the respectively-opposite ends of the aperture or bore 20 to receive the heads of the screws 21 and 22. The screws 21 and 22 are windage adjustment screws and when a telescopic sight is mounted on the mount 10 these screws engage a plate or pedestal near the rear end of the sight to pivot the telescopic sight slightly 35 about the axis of the post received in the opening 16 to compensate the rifle sight for windage. Elevation adjustment means are included in the telescopic sight itself.

While the sight mount 10 has been described in 45 detail, this is a known construction and does not constitute any part of the present invention except in the combination thereof with the detachable or auxiliary sight, the auxiliary sight being adaptable to various types of telescopic sight mounts.

The auxiliary sight itself comprises, in general, an elongated, rectangular base plate or sight holder 26, a flat sight plate 27, an elongated, rectangular button 28, a screw 29 and a coiled 55 compression spring 30.

The sight holder 26 is particularly illustrated in Figure 9 and comprises, a flat, elongated, rectangular plate having at one end a downwardly-turned, perpendicularly-extending flange or supporting member 31 provided with a substantially centrally located, internally screw-threaded aperture or screw hole 32. The base plate is provided intermediate its length and in its respectively-opposite longitudinal edges with notches 33 and 34 providing beveled portions 35 and 36 which are respectively receivable in the concave inner surfaces of the heads of the screws 21 and 22, so that by placing the plate 26 on the top of the rear portion 13 of the mount 10 and tightening the windage screws 21 and 22 against the opposite sides of the plate with the portions 35 and 36 received in the concave inner surfaces of the screw heads, as particularly illustrated in Figure 5, the plate 26 can be firmly attached to the mount 10 for the telescopic sight when the telescopic sight has been removed from the mount. The windage screws 21 and 22 are threaded into the mount substantially equal distances, so that the plate 26 is centered, as nearly as practicable, relative to the longitudinal center line of the mount 10.

The outer surface of the flange 31 is provided with fine serrations 37 which extend perpendicularly to the end of the flange.

The sight plate 27 is a generally square or rectangular plate having its opposite corners at the same end cut away on an angle of approximately 45-degrees and joined by an arcuate curve at the center of the plate to provide a somewhat triangular shape at the upper end of the plate. A sight hole or opening 38 is provided substantially at the center of the area of this triangular upper portion of the plate 27, and immediately below the sight opening 38 the plate is provided with an enlarged, rectangular notch 39. On one side the sight plate 27 is provided with fine serrations 40 which are disposed substantially perpendicularly to the bottom end of the plate and on its opposite side, as particularly illustrated in Figure 4, it is provided with serrations 41 which run substantially parallel to the bottom edge of the plate.

The button 28 is an elongated, rectangular body having a flat inner surface provided with fine serrations 42 which run substantially parallel to the longitudinal side edges of the button and provided with a double beveled outer surface. A bore 43 extends centrally through the button 28 and a counterbore 44 is provided in the bore 43 at the end of the latter opening to the outer surface of the button.

A coiled spring 30 is seated in the counterbore 44 and bears at one end against the inner end of the counterbore. The screw 29 extends through the spring, through the button 28, through the notch 39 in the sight plate 27, and is threaded into the screw hole or aperture 32 in the flange 31 of the base plate 26. This screw has a head which bears against the outer end of the spring 30 and is of a size to marginally engage the button 28 around the counterbore 44 when the screw is tightened.

After the base plate 26 with the sight plate 27 assembled thereon by the screw 29 and button 28, is mounted on the telescopic sight mount 10 in the manner indicated above, the sight plate may be adjusted to compensate the rifle for elevation and windage. This is accomplished by slightly loosening the screw 29 so that the sight plate 27 is clamped between the button 28 and the flange 31 by spring pressure only. The sight plate may

now be forced upwardly relative to the base plate and as the serrations 41 of the sight plate pass the serrations 42 of the button 28, a slight click will be produced for each step or movement of the sight plate relative to the button. The serrations are so graduated that a movement of the sight plate corresponding to the width of one serration will produce a known deflection of the shot at a predetermined distance. For example, one step of the sight plate may raise the shot a distance of one-and-one-half-inches at a range of one-hundred yards. The sight plate may also be moved laterally of the base plate and when such movement is imparted the serrations 40 will pass over the serrations 37 on the flange 31 of the base plate. The serrations 40 and 37 are also graduated to produce a known deflection at a given range, so that the sighting of the rifle can be accurately adjusted for both elevation and windage by proper movement of the sight plate 27 in vertical and horizontal directions. After the proper setting of the sight plate has been obtained, the screw 29 is tightened to firmly lock the sight plate in fixed relation relative to the base plate 26. The notch 39 in the sight plate is of sufficient size to provide the necessary range of adjustment of the sight plate relative to the base plate and the fine serrations on the opposite sides of the sight plate provide a light-deflecting surface which greatly reduces eye strain in sighting a rifle equipped with the detachable or auxiliary sight of the present invention. The entire structure of the auxiliary sight is also preferably given a dark, non-reflecting surface finish to further reduce eyestrain on the marksman using the sight.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A detachable gun sight for mounting on a telescopic sight mount comprising an elongated, rectangular plate having at one end a perpendicularly-extending flange provided with a centrally-located, internally screw-threaded aperture, said plate having intermediate its length and in its respectively-opposite longitudinal edges notches providing portions engageable by the windage screws of a telescopic sight mount, a sight plate having a screw-receiving notch and a sight opening overlying the flange of said first-mentioned plate with said screw-receiving opening in registry with said internally screw-threaded aperture, a button overlying said sight plate opposite said first-mentioned plate flange and having a centrally located bore in registry with said screw-receiving opening and a counterbore in one end of said bore, a coiled spring in said counterbore, and a screw extending through said spring, said button and said second plate and threaded into the screw-threaded aperture in the flange of said first-mentioned plate, said screw having a head which bears against the outer end of said spring and marginally engages said button around said counterbore when said screw is tightened against said button.

2. A detachable gun sight for mounting on a telescopic sight mount comprising an elongated,

2,575,653

5

rectangular plate having at one end a perpendicularly-extending flange provided with a centrally-located, internally screw-threaded aperture, said plate having intermediate its length and in its respectively-opposite longitudinal edges notches providing portions engageable by the windage screws of a telescopic sight mount, a sight plate having a screw-receiving notch and a sight opening therein overlying the flange of said first-mentioned plate with said screw-receiving opening in registry with said internally screw-threaded aperture, a button overlying said sight plate opposite said first-mentioned plate flange and having a centrally located bore in registry with said screw-receiving opening and a counterbore in one end of said bore, a coiled spring in said counterbore, and a screw extending through said spring, said button and said second plate and threaded into the screw-threaded aperture in the flange of said first-mentioned plate, said screw having a head which bears against the outer end of said spring and marginally engages said button around said counterbore when said screw is tightened against said button, said sight plate having on one side fine serrations extending substantially perpendicular to the bottom end thereof and on its opposite side fine serra-

6

tions extending substantially parallel to such bottom end, said button having on its side contacting said sight plate fine serrations extending substantially parallel to the longitudinal side edges thereof, and said flange having on its outer side fine serrations extending substantially parallel to the end thereof.
